UNITED STATES PATENT OFFICE

117,753

DESIGN FOR A BUILDING FRONT

Walter March, West Nyack, N. Y.

Application January 14, 1939, Serial No. 82,354

Term of patent 7 years

To whom it may concern:

Be it known that I, Walter March, a citizen of the United States, residing at West Nyack, Rockland County, New York, have invented a new, original, and ornamental Design for a Building Front, of which the following is a specification, reference being had to the accompanying drawing, forming part thereof.

In the accompanying drawing:

Fig. 1 is a perspective view showing the building front of my new design;

Fig. 2 is a horizontal cross-sectional view taken on the line 2—2 in Fig. 1;

Fig. 3 is a side elevational view, and

Fig. 4 is a front elevational view thereof.

The dominant features of my design reside in the portions shown in solid black lines in the drawing, as shown.

I claim:

The ornamental design for a building front, substantially as shown and described.

WALTER MARCH.
